Patented Sept. 11, 1917.

UNITED STATES PATENT OFFICE.

BETSIE K. H. LOYLAND, OF THIEF RIVER FALLS, MINNESOTA.

SHOE-FASTENER.

1,239,610.

Specification of Letters Patent. Patented Sept. 11, 1917.

Application filed December 4, 1916. Serial No. 135,041.

To all whom it may concern:

Be it known that I, BETSIE K. H. LOYLAND, a citizen of the United States, residing at Thief River Falls, in the county of 5 Pennington, State of Minnesota, have invented certain new and useful Improvements in Shoe-Fasteners; and I do hereby declare the following to be a full, clear, and exact description of the invention, such as will 10 enable others skilled in the art to which it appertains to make and use the same.

The present invention is directed to improvements in shoe fasteners, and has for its object to provide a device of this character so constructed that the shoe can be tightly closed and held closed without the aid of the usual laces and buttons.

A further object of the invention is to provide a fastener so constructed that the 20 upper will be stretched to fit the instep and ankle of the wearer so as to be neat in appearance.

A still further object of the invention is to provide a fastener which can be conveniently applied to the uppers of shoes, and can be easily and quickly actuated to fasten the closure or unfasten the same.

With these and other objects in view, this invention resides in the novel features of 30 construction, formation, combination and arrangement of parts to be hereinafter more fully described, claimed and illustrated in the accompanying drawing, in which:

Figure 1 is a side elevation of a shoe 35 equipped with a fastener.

Fig. 2 is a sectional view on line 2—2 of Fig. 1.

Fig. 3 is a perspective view of one of the 40 disks and arms, when removed from the shoe.

Fig. 4 is a similar view of one of the other disks.

Fig. 5 is a sectional view illustrating the 45 position of one of the arms previous to the engagement of the fastening elements.

Referring to the drawing, 1 indicates a shoe having the usual upper flaps 2 and 3, the latter being provided with a plurality of tabs 4, the purpose of which will appear 50 later.

To the flaps 2 is secured in any suitable manner a plurality of disks 5, said disks being provided with arms 6 and 7, the latter arm being hingedly connected to the adjacent 55 end of the arm 6 and has its free end provided with a curved seat 8. The disk 5

has extending centrally therefrom a post 9, said post being provided with a head 10 while arranged on opposite sides of the post 9 are loops 11, the purpose of which will 60 appear later.

Each fastener further consists of a plate 12, which may be of any shape desired and ornamented to suit the fancy of the manufacturer, said plate having a tubular shank 65 13 carried thereby, which passes through the opening 14 formed in the tab 4, said shank being suitably secured centrally of the disk 15. Thus it will be seen that a portion of the shank 13 will project slightly beyond 70 the inner surface of the associated disk 15, whereby the head 10 will engage in the tubular shank.

Located on opposite sides of the shank 13 are hooks 16, said hooks being adapted to 75 detachably engage the loops 11 carried by the disk 5.

Since the plates 12 are rigidly connected with the disks 15 it is obvious that the plates 12 can be rotated so that the hooks 16 carried by the disks 15 can be engaged or disengaged with the loops 11 upon partially 80 rotating the plates. By providing the arm 7 it is obvious that the same can be positioned with its seat 8 engaged with the 85 grooved periphery of the disk 15, and as the disk 15 is moved toward the disk 5, the flap 3 of the shoe will be stretched. After the shank 13 is alined with the head 10 slight pressure is exerted on the plate 12 where- 90 upon the head will snap into engagement with the tubular shank, after which the plate 12 is rotated so that the hooks 16 carried by the disk will engage the loops 11 carried by the disk 5, thus firmly fastening 95 the flaps of the upper shoe.

From the foregoing description it will be seen that a shoe fastener has been provided which is effective in operation and will in no way detract from the appearance of the 100 shoe, since all parts of the fastener are concealed from view with the exception of the plates 12, which can be ornamented in a way to add to the appearance of the shoe.

What is claimed is:

A shoe fastener comprising a pair of hingedly connected arms, one of said arms having a disk carried thereby, while the other arm is provided with a seat, a head carried by the disk, loops disposed on opposite sides of the head and carried by the disk, means for attaching one of the arms to

the shoe upper, shanks carried by the shoe upper for interlocking engagement with the heads, said shanks having disks carried thereby, hooks carried by the last named 5 disks, means for rotating the last named disks to cause the hooks to engage the loops, said seat being adapted to engage the shank, as the last named disks are moved toward

the first named disks, as and for the purpose set forth.

In testimony whereof, I affix my signature, in the presence of two witnesses.

BETSIE K. H. LOYLAND.

Witnesses:

PAUL MIDDERIGE,
Mrs. C. BENGTSON.
